UNITED STATES PATENT OFFICE

2,456,639

VACUUM CLEANER

Clarence W. Lanter, Bartlett, Ill., assignor to
Breuer Electric Mfg. Company, Chicago, Ill., a
corporation of Illinois

Application November 29, 1946, Serial No. 712,849

7 Claims. (Cl. 183—37)

1

This invention relates to improvements in vacuum cleaners and is more particularly concerned with improvements in vacuum cleaners of the tank type adapted for industrial use.

It is an object of this invention to provide a tank-type vacuum cleaner in which a portable blower and vacuum cleaner unit is demountably positioned on a removable cover provided on the tank.

It is a further object of this invention to provide a tank-type vacuum cleaner embodying improved means for detachably mounting a portable blower and vacuum cleaner unit in operative position upon the cover of the tank.

It is a further object of this invention to provide a vacuum cleaner in which the dirt being collected is first drawn into the interior of the tank in the form of a helical stream to cause the heavier particles of dirt to be directed along the inner wall of the tank and thence downwardly to settle upon the bottom of the tank. Air and relatively light particles of dirt are drawn from adjacent the top center of the tank into the inlet side of the blower for discharge into a dirt collector bag provided on the outlet nozzle of the blower. The heavier particles of dirt are thus collected within the tank of the vacuum cleaner and the lighter particles of dirt are separated from the air stream by means of a dirt collector bag provided at the exit side of the blower.

This invention further contemplates the provision of improved means for detachably connecting and supporting the dirt collector bag upon the outlet nozzle of the blower.

This invention embodies other novel features, details of construction and arrangement of parts which are hereinafter set forth in the specification and claims, and illustrated in the accompanying drawings wherein:

Fig. 1 is a side elevational view showing a vacuum cleaner embodying features of this invention.

Fig. 2 is a rear elevational view of same.

Fig. 3 is an enlarged, fragmentary rear elevational view, partly in section, illustrating the manner of demountably supporting the portable blower and vacuum cleaner unit upon the cover of a tank.

Fig. 4 is a top plan view showing the vacuum cleaner.

Fig. 5 is a sectional view taken along the line 5-5 of Fig. 3.

Fig. 6 is a detail plan view showing a motor clamping handle.

Fig. 7 is a sectional view taken along the line 7-7 of Fig. 6.

2

Fig. 8 is a detail front elevational view showing the motor clamping handle.

Fig. 9 is a detail sectional view taken along the line 9-9 of Fig. 7.

5 Fig. 10 is a detail side elevational view showing a dirt collector bag support.

Fig. 11 is an end view of same.

Referring now to the drawings for a better understanding of this invention, the vacuum cleaner is shown as comprising a portable blower and vacuum cleaner unit 6 generally indicated at 6 and embodying a blower 7 which is driven by an electric motor 8. When the portable blower and vacuum cleaner unit 6 is employed as a

10 vacuum cleaner, air is drawn into the blower 7 through the inlet nozzle 9 and is directed outwardly through the outlet nozzle 11 into a suitable dirt collecting bag 12 formed of fabric. When the unit 6 is employed as a blower, a suitable

15 nozzle (not shown) is positioned on the outlet nozzle 11 of the blower 7. When the unit 6 is employed as a portable vacuum cleaner or blower, it is manually supported by means of a suitable handle 13. As the construction and operation of

20 the portable blower and vacuum cleaner unit 6 is described in detail in a copending application filed May 2, 1946, Serial No. 666,770 in the name of Grant W. Breuer and assigned to the same assignee, it is believed that a further description of the unit 6 will not be necessary to an understanding of the present invention.

The blower and vacuum cleaner unit 6 is adapted to be demountably secured to a cover 14 of a cylindrical tank 16. The cover 14 is provided with an inlet passage 17 leading from adjacent

35 the top center of the tank 16 to direct a stream of air and dirt into the inlet nozzle 9 of the blower 7. The inlet nozzle 9 of the blower 7 is demountably positioned within a suitable adapter 18 which

40 is secured to the outlet side of the passageway 17 by means of suitable screws 19. The adapter 18 is preferably formed of rubber having an inner liner 21 of metal. The unit 6 is adapted to be supported at both ends with an intermediate support of semi-circular strip of rubber 22 disposed within a recess 23 formed in the top surface in the cover 14.

The portable blower and vacuum cleaner unit 6 is clamped in position upon the cover 14 by means of a clamping sleeve 24 mounted for reciprocal movement upon a stud shaft 26, one end of the stud shaft being secured within an aperture 27 of a boss 28 by means of a set screw 29. A rubber disc 31 is molded onto the forward 45 end of the clamping sleeve 24 for engagement

against the rounded end of the motor housing 32. The clamping sleeve 24 is reciprocated along the stud shaft 26 for movement into and out of engagement with the motor housing 32 by means of a clamping handle 33 which is pivotally connected at 34 to the boss 28. The clamping sleeve 24 is actuated by the clamping handle 33 by means of a pair of cam slots 36-36 provided on opposite sides of the clamping handle 33 to receive the ends of a cross pin 37 provided on the clamping sleeve 24.

In mounting the blower and vacuum cleaner unit 6 upon the cover 14, the blower nozzle 9 is first inserted into the adapter 18 with the unit resting upon the semi-circular rubber strip 22. The clamping handle 33 is then moved from its dotted position illustrated in Fig. 3 to its full line position to act through the cam slots 36-36 and cross pin 37 to move the clamping sleeve 24 and rubber facing 31 into clamping engagement against the rounded end of the motor housing 32.

It will thus be seen that the blower and vacuum cleaner unit 6 is secured in position between resilient rubber cushion members 18, 22 and 31 which serve to absorb any vibration of the motor 8 while same is operating. It will also be noted that blower and vacuum cleaner units of different sizes may be mounted upon the cover 14 by merely replacing the adapter 18 with an adapter of different size or shape.

The cover 14 is provided with an annular downwardly facing groove 41 to receive a rubber ring 42 which is adapted to engage against the upper curled edge 43 of the tank 16. The cover is secured against upward displacement by means of a pair of latches 44-44 which are pivotally mounted at 46-46 to diametrically opposed, downwardly extending arms 47-47 formed on the cover 14. The latches 44 are normally held in their positions illustrated in Fig. 3 by means of resilient spring members 48-48 to dispose the upper ends of the latches behind the curled upper edges 43 of the tank 16. To remove the cover 14 from the tank 16, the lower ends 51-51 of the latch members 44-44 are pressed inwardly to move the latches from their latched positions.

The dirt collector bag 12 is provided with a neck portion 53 to receive a bag support 54 comprising a tubular portion 56 and an inverted trough-shaped portion 57. The bag support 54 is inserted into the neck opening 53 of the bag 12, and the neck portion 53 and tubular portion 56 of the support 54 are then secured to the outlet nozzle 11 of the blower 7 by means of a locking nut 58.

In the operation of the vacuum cleaner, a stream of air is drawn inwardly through an intake nozzle 61 leading to the interior of the tank 16 adjacent the upper end thereof. The inner end of the nozzle 61 is provided with a passage 62 for directing the stream of air in a circular direction along the inner wall of the tank. As the air stream passes along the inner surface of the tank 16, relatively heavy particles of dirt tend to fall by gravity toward the bottom of the tank. The lower end 63 of the passageway 17 is disposed to draw air from adjacent the top center of the tank 16, thence through the blower 7 and into the dirt collector bag 12. The location of the passage 62 with respect to the passage 63 is important to prevent relatively heavy particles of dirt from being drawn from the tank through the passageway 17. It is contemplated that a suitable flexible suction hose 66 may be detachably secured to the nozzle 61 by means of a locking screw 67.

While this invention has been shown in but

one form, it is obvious to those skilled in the art that it is not so limited but is susceptible of various changes and modifications without departing from the spirit and scope of the claimed invention.

I claim as my invention:

1. In a vacuum cleaner, a tank having an air inlet, a cover mounted on said tank and formed with an air passageway leading from the interior of said tank to the upper side of the cover, a motor-blower unit having an axial inlet and tangential outlet for the passage of air, a reciprocable clamping jaw provided on said cover to secure the motor-blower unit against displacement and with the axial inlet of the latter in communication with the air passageway provided in the cover, and cam actuating means to move said clamping jaw into and out of clamping engagement with said motor-blower unit.

2. In a vacuum cleaner, a tank having an air inlet, a cover mounted on said tank and formed with an air passageway leading from the interior of said tank to the upper side of the cover, a motor-blower unit having an axial inlet and tangential outlet for the passage of air, a reciprocable clamping jaw provided on said cover to secure the motor-blower unit against displacement and with the axial inlet of the latter in communication with the air passageway provided in the cover, cam actuating means to move said clamping jaw into and out of clamping engagement with said motor-blower unit, said clamping jaw being formed of resilient material.

3. In a vacuum cleaner, a tank having an air inlet, a cover mounted on said tank and formed with an air passageway leading from the interior of said tank to the upper side of the cover, a motor-blower unit having an axial inlet and tangential outlet for the passage of air, a reciprocable clamping jaw provided on said cover to secure the motor-blower unit against displacement and with the axial inlet of the latter in communication with the air passageway provided in the cover, cam actuating means to move said clamping jaw into and out of clamping engagement with said motor-blower unit, said clamping jaw being formed of resilient material, and an adapter formed of resilient material mounted in the air passageway in the cover to snugly engage the axial air inlet of said motor-blower unit.

4. In a vacuum cleaner, a tank having an air inlet, a cover mounted on said tank and formed with an air passageway leading from the interior of said tank to the upper side of the cover, a motor-blower unit having an axial inlet and tangential outlet for the passage of air, a reciprocable clamping jaw provided on said cover to secure the motor-blower unit against displacement and with the axial inlet of the latter in communication with the air passageway provided in the cover, a dirt bag, and a trough-shaped nozzle secured to the tangential outlet of said motor-blower unit to support said dirt bag.

5. In a vacuum cleaner, a cylindrical tank having an air inlet, a cover detachably mounted on said tank and formed with an air passageway leading from adjacent the top center of the tank to the upper side of the cover, a motor-blower unit having an axial inlet and tangential outlet for the passage of air, a stud shaft provided on said cover, a clamping jaw mounted for reciprocable movement along said stud shaft to secure the motor-blower unit against displacement and with the axial inlet of the latter in communication with the air passageway provided in the cover when the axial inlet of the motor-

blower unit is in communication with the air passageway provided in the cover.

6. In a vacuum cleaner, a cylindrical tank having an air inlet, a cover detachably mounted on said tank and formed with an air passageway leading from adjacent the top center of the tank to the upper side of the cover, a motor-blower unit having an axial inlet and tangential outlet for the passage of air, a stud shaft provided on said cover, a clamping jaw mounted for reciprocable movement along said stud shaft to secure the motor-blower unit against displacement from the cover when the axial inlet of the motor-blower unit is in communication with the air passageway provided in the cover, and an air nozzle mounted within the air inlet of said tank to direct a stream of air along the inner wall of the tank.

7. In a vacuum cleaner, a cylindrical tank having an air inlet, a cover detachably mounted on said tank and formed with an air passageway leading from adjacent the top center of the tank to the upper side of the cover, a motor-blower unit having an axial inlet and tangential outlet for the passage of air, a stud shaft provided on said cover, a clamping jaw mounted for recipro-

cable movement along said stud shaft to secure the motor-blower unit against displacement from the cover when the axial inlet of the motor-blower unit is in communication with the air passageway provided in the cover, an air nozzle mounted within the air inlet of said tank to direct a stream of air along the inner wall of the tank, and a pair of latches pivotally mounted on diametrically opposed sides of said cover for engagement with said tank.
